UNITED STATES PATENT OFFICE.

HENRY D. BRISTOL, OF OCEANSIDE, NEW YORK.

MEANS FOR CHECKING SEPARATE ACCOUNTS.

SPECIFICATION forming part of Letters Patent No. 732,271, dated June 30, 1903.

Application filed May 23, 1902. Serial No. 108,676. (No model.)

To all whom it may concern:

Be it known that I, HENRY D. BRISTOL, a citizen of the United States, residing in the town of Oceanside, in the county of Nassau and State 5 of New York, have invented a certain new and useful Improvement in Means for Checking Separate Accounts, of which the following is a specification.

In most cafés and restaurants the wine and cigar accounts are kept separately from those for food, and in some cases oysters, &c., are also charged up on a second account. In the hurry and bustle often incident to his duties a waiter finds it hard to avoid mistakes in proper charging of items to various separate accounts, and in order to provide a check against errors so arising, as well as security against dishonesty, it has become usual to employ a separate "checker," whose duty it is to manage the particular "checking" system adopted in a given restaurant and to see that the various orders are properly charged to one or the other account. Hitherto the best methods employed for carrying out this necessary checking have involved the use of large and cumbersome sheets, and the checker's table has been necessarily so large as to take up much of the space so valuable in city houses. Moreover, the many headings crowded into a sheet of this kind lead to frequent mistakes on the checker's part.

It is the object of this invention to provide a simple and reliable means whereby the above ends can be carried out without the necessity of using the large complicated checker's sheets, and consequently with economy of room and decreased liability of mistake.

In the drawings accompanying this application, Figure 1 is the face view of the end of a roll of "guest-checks" as used in this system. Fig. 2 is a similar view of the end of a roll of "waiter's vouchers" and "checker's duplicates." Fig. 3 is an edge view of one of these rolls. Fig. 4 is a perspective view of one form of checker's desk capable of use with this invention; and Fig. 5 is a perspective view of a duplicate die, preferably used by the checker.

In carrying out this system two sets of perforated or divisible checks are used, which are supplied either in bundles or in rolls. Rolls, such as are shown in Fig. 3, are printed with

successively-numbered checks separated by straight rows of perforations, facilitating tearing off one check after another. As shown 55 in Fig. 1, each guest-check is divided near the right-hand side by a line of perforations *a*, and the upper right-hand corner is squarely separated by an additional line *b*. The square so demarcated bears the number of the check, 60 as "No. 1" or "No. 2," &c. This number also appears, as shown at the head of the column to the right of the perforations *a*, and at the head of the left-hand portion of the guest-check. This number identifies the guest 65 served with the particular items written thereon. The roll or bundle is preferably kept by the checker. The checker is also provided with a roll or bundle of waiter's vouchers, 70 also in duplicate, each voucher being separated longitudinally, as by perforation *c*, and being headed on the two sides, respectively, "Waiter's voucher" and "Checker's duplicate." The numbers "No. 1," "No. 2," &c., 75 shown in the drawings, Fig. 2, are not printed upon these slips as preferably used, as they are not necessarily used for every guest. Where not only wine, but cigars and oysters, &c., are sold under separate accounts, each 80 "voucher" is headed in writing by the checker at the time it is handed out to the waiter. It is at this time, too, that the checker marks the vouchers on both sides of the line *c* to correspond to the guest-check in each case.

To explain the working of this system, the 85 outfit illustrated in Fig. 4 will be taken as merely an illustrative case, it being understood that the rolls, Fig. 3, may be used instead of bundles of checks and that other departures from the exact outfit mentioned 90 may be made without departing from this invention.

The desk *d* is provided with drawers *e* for holding the duplicate checks when detached. Conveniently at hand is an ordered group of 95 duplicate dies *f*. These may be constructed as shown, for instance, in Fig. 5, with a certain number, indicating a sum of money, produced in duplicate and properly spaced to cooperate with the printed checks used in each case. These may be used in connection with a pad or pads *g* in a well-known manner, to print the number (as 25) in duplicate, as hereinafter described. In suitable compart-

ments are stored the various checks, as shown in Fig. 4, a bundle of guest-checks *h* and a bundle of vouchers *i*. When a new guest takes his seat, the waiter attached to his table applies to the checker for a guest-check. He then takes the order, writing down the articles called for—as, for instance, those named on check No. 1 in Fig. 1. This check is taken to the kitchen, and when the waiter carries in the first instalment of the order—as, for instance, roast beef and asparagus—he passes the checker, who verifies the order, tears off the upper right-hand corner of the check with the number, and stamps the proper prices opposite the various items. By using a duplicate stamp, as shown in Fig. 5, this price is printed by a single operation on both sides of the perforations *a*. The checker keeps the square showing the number of the check, as this informs him that the guest-check bearing that number has been used and food delivered on it. This item becomes important in case of loss of the check. If the checker observes that wine or liquor is ordered, as the "1 Bass" in Fig. 1, he not only stamps its price opposite the order on the guest-check in duplicate, but he marks a voucher in duplicate with the number of the guest-check, identifies such voucher as being for wine or cigars, &c., (if necessary,) stamps the price in duplicate or otherwise marks it on both parts of the voucher, (as thirty cents in the drawings,) and then tears the voucher down the middle on the line *c*. The checker keeps the portion marked "checker's duplicate" and the waiter takes the other portion to the bar or other special counter, where he procures the wine, cigars, or other special order by delivering up his voucher. Thus the barkeeper has an evidence of goods delivered to the house and the checker has his duplicate thereof. When the meal is finished, the duplicate columns are added up on the guest-check and the total is written or stamped at the foot of each column. The two sums will of course be identical. When the waiter is paid, he takes the money with the guest-check to the cashier, who, on receiving the money, marks the right-hand or stub portion "paid" or with

the letters "Pd." as in the drawings, or otherwise, to give evidence of payment, and then tears off the said receipted stub, giving it to the waiter, who delivers it to the checker in evidence of the money on that particular order having been paid after due service of the guest. By this means a check is obtained on the cashier, and at the same time by observing the corner-numbers and comparing them with receipted stubs handed in, the checker can ascertain at any moment which orders are still pending and which have been paid, thus preventing the withholding of an accounting on orders out of due season.

It will be seen that by the use of the devices above described a complete checking system is carried out without the necessity of using the clumsy and large checker's sheets, and consequently without the use of the great space otherwise necessary to devote to the checker.

The specific words shown in the drawings may or may not be printed upon the checks and vouchers.

It is to be understood that this invention is capable of use whatever the specific wording of the various printed headings, and that other changes may be made in the details herein shown and described without departing from the spirit of my invention. While the duplicate die is preferably employed, as herein described, its use is not essential to the use of my system in its broadest aspect.

What I claim is—

In apparatus for keeping separate accounts and checking the same, a two-part guest-check partly divided into principal sections by a vertical row of perforations and having the end of one of its sections partly separated by a horizontal line of perforations for forming a corner-section, and an identifying-mark printed both above and below said horizontal line on one principal section and once upon the other principal section.

HENRY D. BRISTOL.
